UNITED STATES PATENT OFFICE.

GEORGIA PARK, OF NEW YORK, N. Y., ASSIGNOR OF ONE-HALF TO W. E. SHOALES, OF PLYMOUTH, NEW YORK.

CLOTHES-LINE CLAMP.

SPECIFICATION forming part of Letters Patent No. 683,138, dated September 24, 1901.

Application filed February 13, 1901. Serial No. 47,119. (No model.)

To all whom it may concern:

Be it known that I, GEORGIA PARK, a citizen of the United States, residing at New York, in the county of New York and State of New York, have invented certain new and useful Improvements in Clothes-Line Clamps; and I do declare the following to be a full, clear, and exact description of the invention, such as will enable others skilled in the art to which it appertains to make and use the same.

The invention relates to clothes-line clamps, and more particularly to clamps used for connecting the ends of the clothes-line frame into an endless line which is adapted to travel around pulleys carried by suitable supports.

The object of the invention is to provide a clamp of this character which shall be simple of construction, durable in use, comparatively inexpensive of production, and which when in position will securely connect together the ends of a rope.

With this and other objects in view the invention consists in certain features of construction and combination of parts, which will be hereinafter more fully set forth.

In the accompanying drawings, Figure 1 is a side elevation illustrating my invention in use. Fig. 2 is a longitudinal sectional view of the clamp, showing the ends of the clothes-line connected thereto and the direction of strain being indicated by the arrows; and Fig. 3 is a detail view of the parts separated.

Referring to the drawings, 1 denotes the frame of the clamp, having a fixed clamping-jaw 2 and provided with a downwardly and forwardly curved slot 3, intersected by a vertical slot 4, which communicates with a chamber 5, contiguous to the fixed jaw 2. The rear end of the frame is provided with a rearwardly-extending lip 6, which is bent slightly downward.

7 denotes a lever provided at one end with a serrated jaw 8, which is adapted to coact with the jaw 2 and clamp the rope in position. The opposite end of this lever is curved upwardly and is formed with an eye 9, with which one end of the rope is adapted to be connected. Intermediate the length of the lever project on opposite sides thereof studs 10, which are adapted to engage the slots 3 in assembling the parts. By casting the lever

with the studs and forming the frame of the clamp with slots the parts may be easily and quickly assembled after leaving the molds, thus overcoming the expense attendant on riveting or heading. In other words, when the parts leave the mold they are assembled and are then in position for immediate use. As shown in Fig. 2, one end of the rope is connected to the outer end of the lever and the other end of the rope is passed under the lip 6, engaged with the groove 10' formed in the lower side of the frame of the clamp, and then inserted upwardly between the two jaws and drawn taut. When the line is under tension, the pull is in the straight line indicated by the arrows in Fig. 2, so that the greater the pull the greater will be the clamping action upon the rope by the jaws. This I accomplish by curving the lever and by providing the lip 6. The function of this lip 6 is to provide an extended bearing acting in the nature of a fulcrum binding upon the clamped end of the rope, so that when strain is applied to the rope in the direction indicated by the arrow the clamp is given a tighter bearing upon the end of the rope.

From the foregoing description, taken in connection with the accompanying drawings, the construction, operation, and advantages of my invention will be readily understood without requiring an extended explanation. The device is exceedingly useful for the purpose for which it is designed and may be placed upon the market at a comparatively small cost.

Various changes in the form, proportion, and the minor details of construction may be resorted to without departing from the principle or sacrificing any of the advantages of this invention.

Having thus fully described my invention, what I claim as new, and desire to secure by Letters Patent, is—

A rope-clamp, comprising, in combination, a frame provided with a fixed jaw and with a downwardly and forwardly curved slot intersected by a vertical slot, said fixed jaw having a curved downwardly-projecting and outwardly-extending lip adapted to bear upon the clamped end of the rope and to act as a fulcrum for obtaining a tighter bearing upon

the end of the rope, and a lever located in the vertical slot and provided with studs which are seated in said downwardly and forwardly curved slot, said lever being provided with a jaw coacting with the said fixed jaw, substantially as described.

5 In testimony whereof I have hereunto set

my hand in presence of two subscribing witnesses.

GEORGIA PARK.
